UNITED STATES PATENT OFFICE.

CHARLES H. WILDER, OF NATICK, MASSACHUSETTS, ASSIGNOR TO THE HUB CARBON COMPANY, OF KENNEBUNK, MAINE.

MOLD FOR FORMING PIECES OF CARBON FOR ELECTRIC PURPOSES.

SPECIFICATION forming part of Letters Patent No. 376,019, dated January 3, 1888.

Application filed February 26, 1887. Serial No. 239,068. (No model.)

To all whom it may concern:

Be it known that I, CHARLES H. WILDER, of Natick, in the county of Middlesex and Commonwealth of Massachusetts, have invented a new and useful Mold for Forming Pieces of Carbon for Electric Purposes, of which the following is a specification.

My invention relates more particularly to the formation of carbon pieces for the cells of chemical electric batteries, the object of it being to provide a simple and effectual apparatus by which a hollow cylindrical piece of carbon can be formed and baked ready for use; and it consists in the construction and relative arrangement of the several parts which together constitute the complete mold, as hereinafter described, and illustrated by the drawings.

The mold consists of a pedestal or base, a core which is a vertical cylinder cut longitudinally in three pieces, with a stem at the bottom which sets in a socket in the pedestal, an outer wall of diameter enough greater than that of the core to make space between them, in which to pack the substance which is to make a hollow cylindrical piece of carbon made of two pieces of sheet metal, one within the other, secured in place by jointed metallic hoops, a piece of sheet metal closely enveloping the core, and a cast-iron cap or head for both ends of the mold when the core is removed and clamps to hold the heads in place.

Figure 1 shows a perspective of the base or pedestal on which the other parts of the mold are erected and sustained. This is a rectangular block cut in two equal parts on a line through the middle, with a hinge at one end upon which it will open and a hasp and staple at the opposite end by which the two parts are secured in contact with each other. In the center of this pedestal is a hole through it, which is a socket, in which a stem at the bottom of the core of the mold will stand and is held in place. The core of the mold is of wood, cylindrical in form, having a stem at the bottom to set in the socket in the pedestal, and another stem on the center of the top of it to hold and handle it by. The body of it, which is the core and is in use within the shell of the mold, is cut vertically in three pieces, the middle piece of it being in the form of a wedge, with the thicker end upward, the two outside pieces being of a wedge form with the

thick ends downward—the three pieces together making a solid cylinder. Fig. 2 is a top horizontal plan of Fig. 1, showing in the socket 55 a cross section of the core of the mold in it, and the hinge and hasp which secure the two parts of the pedestal together. Fig. 3 is a vertical inside face view of one of the side pieces of the core of the mold and a cross-section of the same 60 on the line Z. Fig. 4 is a side elevation of the core with the loose side piece off. Fig. 5 is an edge view of one of the side pieces of the core shown in Fig. 3. Fig. 6 is a vertical longitudinal section of the pedestal, core, and 65 outside shell of the mold with the carbon piece in its place between the shell and the core. Fig. 7 is a vertical sectional view of the mold with the carbon formed in the space for it, the core removed, the heads placed on both 70 ends of it and clasped in place, and the space where the core was filled with sand, the whole ready to be placed in the coking-oven. Fig. 8 shows a vertical perspective of the outer wall of mold, between which and the core the material for the carbon piece is packed with adjustable hoops. This is a double wall of two 75 separate pieces of sheet metal, both cut open vertically, the edges of the inner one abutting and the edges of the outer one lapping over each other. Fig. 9 shows a perspective of the carbon piece completed, a piece broken out to show the thickness of its walls with a post formed on the top edge integral with the body of it. Fig. 10 shows a perspective of the top 80 head of the mold with a form for the post on the top edge of the carbon. Fig. 11 shows a perspective of the bottom head of the mold. Fig. 12 shows a jointed hoop used to secure the vertical wall of the mold, as shown in Fig. 8. 85 Fig. 13 shows a top edge of a carbon piece with a post on the side of it. Fig. 14 shows a cross-section of the core, with an envelope of sheet-iron around it to separate it from the carbon.

a marks the socket in the pedestal. 95

a' marks the core, cut in three pieces, with its stem at the bottom to set in the socket in the pedestal, and a similar one at the top to handle it by and withdraw the middle wedge-shaped piece when it is to be removed from 100 the mold, thus releasing the side pieces, which can then be easily lifted out.

a² marks the outer wall of the mold, which consists of two sheets of iron wrapped into

cylindrical form, one within the other, the edges of the inner one abutting and the edges of the outer lapping by. These are secured by two metallic hoops, both jointed and hinged.

5 a^3 marks the inner wall of the mold, which is also a sheet of iron wrapped around and on the surface of the core.

a^4 marks the carbon piece in the mold.

a^5 marks the top head for the mold on the mold, showing the elevation for the post on the carbon.

a^6 marks the lower head of the mold.

a^7 marks the clamps which hold the heads of the mold on. When the heads are on, the

15 hoops may be removed.

a^8 marks the space in the center of the mold from which the core has been removed before the heads are put on, and which is filled with sand, which remains there while the mold with

20 the carbon is in the coking-oven and until it

is cooled so that it can be handled.

a^9 marks the jointed hoops which encircle

the outer shell of the mold.

When the core a' is set in the socket in the pedestal with its covering of sheet-iron around it, and the outer shell of the mold placed in its groove on the pedestal and encircled by its hoops, the mold is ready for the materials which are to make the formed carbon piece

30 in it, which are of pulverized coke mixed with

a combination of roofer's pitch and coal-tar, to make its particles cohere. The mixture of coke and pitch and tar, as thick as stiff mortar, is then, by pressure or ramming, forced into the

35 space between the outer shell of the mold and the core. The amount of force or ramming

will determine the density of the carbon piece. The elevation on the top of the upper head is also filled with the mixed coke to make the

40 post on the top edge of the carbon piece. The

core is then withdrawn, and also the sheet-iron envelope which inclosed it. I then prepare a lining which will fit the inside of the

45 carbon as it is in the mold of paper coated with graphite, and put it in place. I then re-

turn the sheet-iron lining to its place within the carbon. I then place the top head on the

50 mold, and turn the mold over so that the bottom end of the mold is upward. I then fill

55 the cavity where the core was with sand, and then put the bottom head in place and secure it by clamps. The mold, with the carbon in it, is then ready for the coking-oven. The paper

lining coated with graphite is for the purpose

55 of preventing the plastic mass from adhering to the metal lining, and it falls to pieces after the coked carbon comes out of the mold.

The whole is placed in an oven or furnace and heated to a bright red for about two or three

60 hours, which will convert the roofers' pitch and tar in the substance in the mold into coke, so that the whole of the substance of the formed piece in the mold is coke. When it

65 has all become coke, the mold, with its con-

tents, is taken out of the coking-oven and buried deep in a bed of sand or ashes, where it is al-

lowed to remain until cool enough to be han-

dled. After the formed carbon has been re-
moved from the mold, it is ready for use again.

I have above described a mold suitable for 70 only one form of carbon piece, but the im-
portant useful features of the mold may be
combined in molds for other forms. The me-
tallic substance of the walls and heads of the
mold are expanded by the heat during the 75
baking or coking of the carbon piece in it,
as well as the carbon piece; but when cooled,
the oven contracts, but the carbon piece does
not contract, and it would be crushed and
spoiled by the contraction of the iron if the 80
outer wall of the mold was not cut open lon-
gitudinally, so that it can accommodate the
rigidity of the carbon; and a similar result
would ensue if the inside sheet-iron lining
was not cut longitudinally. 85

I claim as new, and my invention—

1. The combination of the pedestal, the sec-
tional core composed of wedge-shaped sec-
tions, the sheet-metal envelope surround-
ing said core, and the outer shell of larger dia-
meter encircling the core and its envelope, sub-
stantially as described. 90

2. The combination of the pedestal having a
socket, the sectional core provided with a stem
for said socket, and the outer wall of larger 95
diameter than said core and surrounding the
latter, substantially as described.

3. In a mold for forming cylindrical carbon
pieces, the lining of graphite paper between
the carbon and the inner metallic wall of the
mold. 100

4. In a mold for forming pieces of pure
coke-carbon of cylindrical form, in combi-
nation with the heads of the mold, vertical
outer and inner walls of sheet metal cut open 105
longitudinally, substantially as described.

5. The combination of the inner sheet-metal
lining, the sand filling within said lining, the
graphite lining outside said sheet-metal lining,
the outer wall of larger diameter for inclosing 110
the annular carbon between it and said inner
lining and the heads, substantially as described.

6. The combination of the inner sheet-metal
lining, the sand filling within said lining, the
graphite lining outside said sheet-metal lining,
the outer wall of larger diameter for inclosing 115
the annular carbon between it and said inner
lining and the heads, one of which is provided
with a hollow elevation, substantially as de-
scribed.

7. The above described improved mold for
forming hollow cylindrical pieces of coke-car-
bon, consisting of the pedestal with a socket
in it, the cylindrical core of wedge-shaped
sections having a stem to enter the socket in 125
the pedestal, the sheet-metal detachable en-
velope around the core, and an outer shell of
larger diameter surrounding the core and its
envelope, substantially as described.
